UNITED STATES PATENT OFFICE.

WILLIAM H. STEPHENSON, OF BLUFFTON, INDIANA.

DETACHABLE SAFETY-CAP FOR LAMP CHIMNEYS OR GLOBES.

SPECIFICATION forming part of Letters Patent No. 592,922, dated November 2, 1897.

Application filed February 19, 1897. Serial No. 624,167. (No model.)

To all whom it may concern:

Be it known that I, WILLIAM H. STEPHENSON, a citizen of the United States, residing at Bluffton, in the county of Wells and State 5 of Indiana, have invented certain new and useful Improvements in Detachable Safety-Caps for Lamp Chimneys or Globes; and I do hereby declare the following to be a full, clear, and exact description of the invention, such 10 as will enable others skilled in the art to which it appertains to make and use the same.

This invention has relation to improvements in devices applicable to lamp chimneys and globes; and it consists in the novel construction and arrangement of a detachable cap adapted to be applied to the upper portion or top of a lamp-chimney or similar article, all 15 as will be hereinafter fully explained.

The annexed drawings, to which reference 20 is made, fully illustrate my invention, in which—

Figure 1 represents a vertical sectional view of my device. Fig. 2 is a side elevation of the same. Fig. 3 is a top view of the cap, 25 and Fig. 4 is a top view of the plate.

Referring by letter to the accompanying drawings, A designates an ordinary lamp chimney or globe, and B designates the cap therefor.

30 C indicates a plate having upwardly-extended arms or lugs a a, which pass through slots a' a' in the cap, whereby the plate is suspended and secured to said cap. The arms a a, after being passed through the slots, 35 are bent at right angles to the main arm, thus combining the two pieces, and when the cap is removed the under plate goes with it. This cap is perforated on the top, as shown at b, and is provided with an annular down- 40 wardly-projecting flange c, having its edge scalloped, one or more of which may be bent inwardly to secure the cap to the top of the chimney, as shown at d.

The cap rests upon the top of the chimney 45 and supports the inner plate, which latter is preferably constructed of sheet metal, having a central opening e, whereby the ventila-

tion is given to the flame in connection with the perforations in the cap. The inner suspended plate above the flame or light, located 50 within the edge of the top of the chimney, is somewhat below the cap, leaving a space between said plate and cap, as shown at f in the drawings, presenting a receptacle for any insects, bugs, or flies which may get through 55 the top perforations and preventing said flies and insects from entering the lamp chimney or globe, and by this arrangement of parts the current of air is broken up, which prevents the fluctuating of the flame, producing 60 a steady flame or light. It also checks and radiates the heat within the chimney, thus equalizing the expansion and contraction of the chimney or globe, avoiding breakage, as well as to prevent igniting of any combustible 65 material which may be above the chimney.

It will thus be seen that my safety device in the form of a perforated cap not only 70 equalizes the heat within the chimney or globe, but prevents the flame from flickering and excludes flies, insects, &c., from the interior of the chimney, and in use the cap can rest upon the chimney without being fastened thereto by the depending scallops..

A device as herein shown and described is 75 simple in construction, durable, ornamental, as well as cheap to manufacture.

What I claim, and desire to secure by Letters Patent, is—

A cap for lamp-chimneys consisting of the 80 inner depending plate provided with one or more openings therein and upwardly-extended arms in combination with the cap having the perforations and flange and holding-fingers and slots adapted to receive the 85 arms of the lower plate whereby the two parts are attached together, substantially as described.

In testimony whereof I affix my signature in presence of two witnesses.

WILLIAM H. STEPHENSON.

Witnesses:

WILLIAM H. PARK,
NATHAN LINN.
